ART OF VAPORIZING FUEL.

Application filed April 15, 1922. Serial No. 553,281.

This invention relates to the art of vaporizing fuel, pertaining more particularly to apparatus adapted for use in vaporizing fuel used for the operation of internal combustion engines.

The present invention is designed more particularly for use in producing a charge of vaporized fuel adapted for use, for instance, in the starting of an internal combustion engine—thus having characteristics of a priming charge—or the charge may be a supplemental or auxiliary charge adapted to augment the usual charge under abnormal conditions encountered in the operation of the engine.

As is well known, more or less difficulty is had in starting an engine of this type installed, for instance, on a motor vehicle, when the engine is "cold"; at such time the parts of the engine are unheated, and it becomes more or less difficult to set up conditions of proper vaporizing of the fuel necessary to provide for engine operation; the fuel is in liquid form, and while there is the presence of suction, and air is admitted, the fuel is not given the atomization or vaporization such as is provided when the engine has been operated and has "warmed up".

This difficulty is especially manifested during the colder months of the year when the air is itself at low temperature. And in this is found one of the reasons why it becomes necessary to employ excessive cranking of the engine—where starting is by the use of a crank—or an excessive operation of the starting motor—when the starting is by the use of a power device.

The present invention is designed to meet conditions of this kind, the purpose being to produce a vaporized charge of a generally sufficient amount for the purpose, with rapidity, so that initial charges delivered to the intake manifold of the engine have the characteristics of the charges developed when the engine is in normal running condition. In addition, the apparatus for producing this type of charge may also be rendered active for the purpose of augmenting the ordinary charge to meet abnormal conditions where a sudden demand for power makes it necessary to supply an augmented charge without delay.

The result is obtained by the use of an apparatus which, as a part of its structure, includes a retort formation into which fuel

is delivered at will and in which the delivered fuel is subjected to the action of heat such as will rapidly vaporize such fuel content. The invention preferably delivers a predetermined amount of fuel to the retort, thus permitting practical assurance of the development of the proper amount and character of vapor in a practically definite time period, thus making it possible to produce practically the same amount of vapor within the same time period whenever the apparatus is placed in use; and this result is better assured by the use of a heating formation in the form of an electrical heating coil, since the time required to bring the heating element to its operating temperatures is short and more or less uniform in successive use.

Other features are present, as presently described, as, for instance, the general formation of the apparatus which enables the reservoir to be readily filled, the substantially concurrent delivery of fuel and closing of the circuit to the heater, the simple and efficient construction, the ease of installation, and the relatively low cost of manufacture.

To these and other ends, therefore, the nature of which will be readily understood as the invention is hereinafter disclosed, said invention consists in the improved construction and combination of parts herein-after more fully described, illustrated in the accompanying drawings, and more particularly pointed out in the appended claims.

In the accompanying drawings, in which similar reference characters indicate similar parts in each of the views,—

Figure 1 is a side elevation of a portion of an internal combustion engine of a well known type with the present invention located in a position of use thereon.

Fig. 2 is a central longitudinal sectional view of the apparatus of our invention, parts being shown in elevation.

Fig. 3 is a view in elevation of the structure shown in Fig. 2.

Figs. 4 and 5 are detail sectional views showing different positions of the fuel charge segregating structure.

Fig. 6 is a sectional view taken on the line 6—6 of Fig. 2.

Fig. 7 is a sectional view taken on line 7—7 of Fig. 3.

Fig. 8 is a view showing a portion of the

structure of Fig. 2 but applied to the engine in a different way from that shown in Figs. 2 and 3.

Fig. 9 is a view in elevation of the device located on the engine at a different point from that shown in Fig. 1, the view omitting some of the parts shown in Fig. 1.

Fig. 10 is a detail elevation, and

Fig. 11 is a transverse section of a portion 10 of a modified mounting for the device, only a portion of the latter being shown.

For the purpose of illustrating the invention we have shown it as applied to an internal combustion engine such as is employed in the well known Ford car, the upper portion of the engine being shown in Fig. 1, in which *a* indicates the intake manifold, the carburetor being indicated at *c* and having the usual air intake pipe *c'*.

20 In Fig. 9, which represents a different installed position of our invention, we have shown simply the carburetor *c* and a portion of the manifold *a*, it being understood that a suitable air intake will be provided leading to the carburetor.

The invention is shown generally in Figs. 2 and 3, these figures indicating the invention as located in the position of Fig. 1, with the structure mounted upon the air intake 30 *c'*.

35 The structure generally is in the form of a casing 15 made up of a retort portion 16, a reservoir portion 17 and a charge-segregating portion 18, the latter being located between the retort and reservoir portions.

40 As shown in this particular form of the invention, the retort is of the open-bottom type, the retort being of suitable configuration in cross section—shown as circular—with the lower open portion of the casing having a configuration such as will readily seat on the air intake *c'*, a suitable gasket *d* being interposed between the pipe and the casing, the casing being removably secured 45 in position by suitable means, such, for instance, as a member 15^a removably held in position by screw 15^b. The air intake is in open communication with the retort through an opening *c'*, this opening extending through the wall of the air intake as well as gasket *d*.

55 The retort is of a suitable vertical height and is designed to carry a vaporizing element of suitable character but which is preferably of the type shown in the drawings. This element preferably comprises a core 19 of suitable dimensions and of suitable material—asbestos for instance—and a heating coil 20, the latter being preferably 60 formed as shown in the drawings in which one end, 20^a, is secured to casing 15 by suitable means, as for instance, a screw, then passing axially through the core and laterally to the periphery of the core where it is 65 coiled about the core, the opposite end por-

tion 20^b then being led outward through an opening 16^a of the casing portion which forms the wall of the retort such end then passing to a binding-post 21 carried by a suitable insulating block 22. The coil is of the high resistance type, such for instance as is formed from Nichrome wire.

70 Since end 20^a is located at the top of the core, it will be readily understood that the heating unit thus produced is practically suspended from such end of the coil, the core extending downwardly, preferably in the axis of the retort and above and spaced from the opening *c'*. As shown, the overall 75 diametrical dimensions of the core are materially less than the diameter of the retort, and since the upper end of the heating unit is also spaced from the top wall of the retort, it will be seen that the heating unit 80 practically forms a central fuel receiving 85 structure of dimensions such as are materially smaller than those of the retort itself, thus providing a free space of comparatively large dimensions within the retort 90 for the free movement of the vapors generated when the coil is active, as presently described.

95 Reservoir 17 forms the upper portion of the casing and is of considerable dimension in order that a considerable quantity of fuel may be located therein. The upper end of the casing is shown as formed with an opening 17^a adapted to be normally closed by a cover 23, opening 17^a being designed for use as a reservoir filling opening, 100 cover 23 forming a closure for the reservoir. A simple means is shown for the purpose of retaining the cover normally closed, this means being shown as a coil spring 23^a having one end secured to cover 23, the opposite 105 end being secured to a loop 24^a of a member 24 having the general configuration shown in Fig. 2, one end being designed to contact a shoulder at the top of the reservoir, the other end being held in contact with a vertical 110 wall of the reservoir through the pull of spring 23^a. The structure provides an arrangement which will retain the cover seated and yet permit it to be raised bodily or canted to permit introduction of a spout 115 of a suitable filling can whenever desired. Obviously, if it is desired to remove the cover, it is only necessary to raise the cover sufficiently to permit access to the interior 120 of the reservoir and then shift the upper end of member 24 to bring it to opening 19^a whereupon the entire structure may be removed.

125 The reservoir 17 and retort 16 are shown as spaced apart by a web 25 of considerable thickness, this web 25 being shown as provided with a tapered recess 25^a which has its axis extending transverse and intersecting the axis of the casing, the recess 130 extending from the front face of the casing

to a depth sufficient to extend adjacent the rear face of the casing, thus carrying the recess some distance beyond the axis of the casing. This recess is adapted to receive a plug 26 of complementary peripheral contour to the recess, the tapered portion of the plug being preferably of less length than the depth of the recess; the plug has some of the characteristics of the usual turning plug, being designed to control the passage of fuel from reservoir 17 to retort 16, portion 25 being provided with openings 25^b and 25^c, these being arranged, in the specific embodiment shown, in axial alinement.

15 However, plug 26 is designed to serve an additional purpose, viz: that of controlling the amount of fuel that can be transferred from the reservoir to the retort at any single operation of the plug. This result is obtained by arranging the ports of the plug as shown more particularly in Figs. 4 and 5, port 26^a, which co-operates with opening 25^b being out of axial alinement with port 26^b—which co-operates with port 25^c—both 20 ports 26^a and 26^b, however, extending radially from a longitudinal port 26^c, the latter port being open to the bottom of recess 25^a, although this latter is not absolutely essential.

30 As will be seen in Fig. 4, in which the plug is at one extreme of its movement, openings 25^b and 26^a are in alinement, while port 26^b and opening 25^c are out of communication; in this position fuel can pass from the reservoir 35 into the space provided by openings 25^b, 26^a, 26^c, the space at the bottom of recess 25^a and port 26^b, this space being filled and remaining filled while the plug is in this position. If, however, the plug be shifted so as to bring 40 port 26^b into registration with opening 25^c, as in Fig. 5—the opposite extreme of movement of the plug 26—communication with the reservoir 17 will be shut off and this content referred to—with the exception of 45 that within opening 25^b—is free to flow into the retort 16 through opening 25^c, excepting possibly that portion in recess 25^a below opening 26^c. To permit this content to readily and quickly pass into the retort, we 50 preferably provide an air inlet port 25^a which, when the plug is in the position of Fig. 5, registers with port 26^a, but which is closed at the plug end when the parts are in the position of Fig. 4.

55 As opening 25^c is preferably arranged in approximate alinement with the axis of the heating unit, it will be readily understood that the content of definite amount of fuel thus discharged through opening 25^c passes 60 directly on to the core 19 of the heating unit. And as the latter is of such material as will permit the fuel to readily permeate the core, it will be obvious that this definite charge of fuel will be quickly distributed 65 within the core and thus be in a favorable

position and condition to be rapidly vaporized upon application of heat to the core, this latter being the function of the heating coil which is adapted to be connected up to a suitable source of current supply as presently described. By reason of the fact that the heating unit remains unchanged as to dimensions, has a practically definite time period in which to reach its active temperature value, and the charge is of definite amount of fuel, it will be readily understood that the time-length for vaporizing this charge can be predetermined because of the possibility of control of the dimensions and characteristics of the heating unit, the current supply, and the amount of fuel within the charge, thus insuring that vaporizing of successive charges will be of similar characteristic and making possible the completion of the vaporization with rapidity. 70 Hence, it is possible to bring the engine into running condition without extensive cranking, either by hand or by starter structure.

In addition to segregating and delivering the charge, plug 26 has the additional function of making and breaking the circuit through the heating coil 20, the plug, which carries insulating members 27, being provided with a finger 28 which is designed to be moved into and out of position between a pair of contact fingers 29 and 30 carried by the insulating member 22. Finger 29 is carried by or connected to binding-post 21, while finger 30 is carried by or connected with a second binding-post 31 which is connected up with the source of electrical supply (not shown) by a lead 32. As shown in Fig. 6, the insulating member 22 is arranged in such manner that fingers 29 and 30 are permanently out of contact—although they are arranged to have their free ends side by side—the member or finger 28 being designed to bridge the gap between the free ends of fingers 29 and 30, thus breaking the circuit through the heating coil; Fig. 3 shows the position of the turning plug when the latter is in the position shown in Fig. 4.

The turning plug is normally held in this position to break the circuit—the position of Fig. 4—by means of a spring 33 which connects a handle 34 carried by the plug and a suitable member 35 carried by one of the screws 15^b. In this position, the turning plug is in communication with the reservoir 17 and thus receives and contains the charge to be vaporized, the structure being inactive at this time, the circuit through the heating coil being broken in the gap between fingers 29 and 30. If, however the handle or lever 34 be rocked upwardly in Fig. 3, the plug 26 will be shifted to bring its ports into the position of Fig. 5, and at the same time close the circuit at the make and break point provided by fingers 29 and 30, with the result that concurrently with the dropping of the 115 120 125 130

charge on to core 19, the circuit will be completed through coil 20 which is quickly brought to active temperature to set up the vaporizing action.

5 This movement of the lever 34 is provided by a suitable operating member 36 which has one end connected to the lever, the member being carried to a point where it can be readily manipulated to set up this movement of the 10 lever; for instance, member 36 may extend to the instrument board of the motor vehicle, or it may extend to a point adjacent to the hand crank. Obviously, spring 33 will return the lever to the position in Fig. 3 whenever member 36 is released. To limit the 15 throw of lever 34, we preferably employ a pair of stops 37, located at proper points.

20 The plug may be held in position in any suitable manner; the simple arrangement shown in the drawings has a spring element 38 carried by the casing and which has its free end active on the outer end of the plug, the member thus tending to retain the plug in its seat and at the same time automatically 25 take up any slight wear that might be had as well as permit relief should there be any tendency of the plug to stick.

30 It will be understood, of course, that the device is designed to be rendered active at the time of starting, the operator manipulating member 36 about the time he begins the cranking operation, so that the suction action set up will become effective in withdrawing the vapor from the retort through 35 the operative connection of the fuel intake *a* and openings *c*², air inlet port 25^a acting as a vent which will permit of the rapid drawing of the content from the retort into the connections leading to the intake *a*. 40 As a general rule, the amount of fuel in the charge will be sufficient when vaporized, to supply the requisite amount of gas to effect efficient starting action, and this vapor will be provided in a comparatively 45 short time so that the operator need not retain the member 36 in its vapor producing position for any extended length of time; in fact, any attempt to extend this length of time acts simply to use up electricity in the heating coil, and thus become 50 a waste. Since release of member 36 returns the plug to the position of Fig. 4 and thus provides a new charge, any necessity for using a second charge of gas can 55 be readily had by simply repeating the operation.

60 And it will be understood, of course, that the apparatus may also be rendered active in the same way during running of the engine as, for instance, when abnormal conditions arise which require a larger charge than that supplied ordinarily for a short period, the vapor from the retort being added to that supplied through the carbureter to augment the charge at such time.

The device may be employed on either side of the carbureter, Fig. 1 illustrating the device as positioned in advance of the carbureter, so that the vapor charge produced, is delivered to the intake through 70 the carbureter, the heated condition of this charge aiding in the carburetting action. Or, as shown in Fig. 9, the device may be located in rear of the carbureter—between 75 it and the fuel intake. In either case, the vapor content reaches the fuel intake of the engine and becomes a part of the engine operating charge.

80 As shown in Fig. 8, the device need not be mounted directly upon or above the air intake *c*', but may be secured to a separate element 40 through which the vapor content of the retort may pass into the line leading to the fuel intake *a*.

85 And in Figs. 10 and 11, is shown still another modified arrangement of the support, the air intake being connected up to a member 41 which acts to support the device, this member taking on the form of a compartment opening into the retort and 90 into the air intake. This particular form may be fabricated at the manufactory of the device, the air intake being a pipe which is connected up to casing 15 by screws 42, the air intake *c*² of this form being arranged 95 to permit its ready positioning with respect to the carbureter or to the fuel intake or both, depending upon the place where it is desired to install the device.

100 In the particular embodiment shown, we have employed an electric circuit in which one side is grounded at the screw 29^c. It will be understood, however, that the grounded portion of the circuit may be replaced by a direct lead to the battery or 105 other source of current supply.

110 And while we have shown the reservoir and retort as an integral structure, it will be readily understood that the portion of the instrumentality shown as unitary, may be an assembly or fabricated formation, the various elements being connected together in any suitable and obvious manner.

115 As will be understood, the structure is simple and efficient in operation, durable in construction and can be manufactured at a relatively low cost.

120 Claims to the specific heating unit are presented in a divisional application filed September 10, 1923, Serial No. 661,774.

125 While we have herein shown and described various embodiments of the invention, it will be readily understood that changes or modifications therein may be found desirable or essential in meeting the various exigencies of use, and we desire to be understood as reserving the right to make any and all such changes and modifications as may be desirable or essential, in so far as the same may fall within the spirit and 130

scope of the invention and as expressed in the accompanying claims when broadly construed.

Having thus described our invention, 5 what we claim as new is:

1. A vaporizing instrumentality for internal combustion engines comprising a casing having a retort portion and a fuel reservoir in superposed relation and spaced apart, a heat-vaporizing unit operative within the retort, and means interposed between the retort and reservoir for transferring fuel from said reservoir to the unit in the retort at will, said means including 10 a movable member operative to segregate a charge from the reservoir and deliver it to the unit.

2. A vaporizing instrumentality for internal combustion engines comprising a casing having a retort portion and a fuel reservoir in superposed relation and spaced apart, a heat-vaporizing unit operative within the retort, and means interposed between the retort and reservoir for transferring fuel from said reservoir to the unit in the retort at will, said means including a movable member having substantially non-concurrent communication with both reservoir and retort, said member being movable 25 between two extremes of movement, the movement from one extreme to the other in one direction being operative to segregate a charge from the reservoir and deliver it to the unit.

3. A vaporizing instrumentality for internal combustion engines comprising a casing having a retort portion and a fuel reservoir in superposed relation and spaced apart, a heat-vaporizing unit operative within the retort, and means interposed between the retort and reservoir for transferring fuel from said reservoir to the unit in the retort at will, said means including a movable member having substantially non-concurrent communication with both reservoir and retort, said member being movable 40 between two extremes of movement, the movement from one extreme to the other in one direction being operative to segregate a charge from the reservoir and deliver it to the unit, the movement in the opposite direction placing the member in position to receive the fuel for the succeeding charge.

4. A vaporizing instrumentality for internal combustion engines comprising a casing having a retort portion and a fuel reservoir in superposed relation and spaced apart, a heat-vaporizing unit operative within the retort, and means interposed between the retort and reservoir for transferring fuel from said reservoir to the unit in the retort at will, said means including 55 an element movably rotatively between two positions, said element having a pair of

communicating ports, said ports being adapted to communicate with the reservoir and retort respectively and positioned to prevent communication between reservoir and retort when the element is in either of its extremes of movement.

5. A vaporizing instrumentality for internal combustion engines comprising a casing having a retort portion and a fuel reservoir in superposed relation and spaced apart, a heat-vaporizing unit operative within the retort, and means interposed between the retort and reservoir for transferring fuel from said reservoir to the unit in the retort at will, said means including 60 an element movably rotatively between two positions, said element having a pair of communicating ports, said ports being adapted to communicate with the reservoir and retort respectively, said ports extending radially and having their outer ends relatively positioned to maintain closure of one of such ends when the other end is in complete open position.

6. An instrumentality as in claim 1 characterized in that the member is in the form of a tapered turning plug carried by the casing and having a limited movement rotatively, said plug having a pair of communicating ports which communicate respectively with the reservoir and retort through casing openings, the ports and openings being relatively positioned to prevent fuel passage from one opening to the other through the ports when the plug is 70 in either extreme of its movement.

7. An instrumentality as in claim 1 characterized in that said means also includes an air vent active through the member during the fuel-transferring activity.

8. An instrumentality as in claim 2 characterized in that the means also includes an air vent active through the ports when the member is in the charge segregating and delivering position.

9. An instrumentality as in claim 2 characterized in that the means also includes an air vent adapted to communicate with said ports by movement of the member to its charge segregating and delivering position and be maintained active while the member is in such position.

10. A vaporizing instrumentality for internal combustion engines comprising a casing having a retort portion and a fuel reservoir in superposed relation and spaced apart, a heat-vaporizing unit operative within the retort, and means interposed between the retort and reservoir for transferring fuel from said reservoir to the unit in the retort at will, said means including a movable member operative to segregate a charge from the reservoir and deliver it to the unit, said heating unit including an electrically-operated heating coil and a fuel-

charge receiving formation supported by the coil.

11. An instrumentality as in claim 10 characterized in that the coil receiving formation are of less dimensions than the internal dimensions of the retort.

12. An instrumentality as in claim 10 characterized in that the receiving formation comprises a plug having the characteristic of supporting and diffusing the delivered charge.

13. An instrumentality as in claim 10 characterized in that the receiving formation comprises a plug of fibrous material.

14. An instrumentality as in claim 10 characterized in that the receiving formation comprises a plug of asbestos.

15. An instrumentality as in claim 10 characterized in that the circuit for the heating coil includes a make and break switch positioned to be rendered active to close the circuit when the member is in charge segregating and delivering position.

16. An instrumentality as in claim 10 characterized in that the heating coil circuit includes a make and break switch having a movable element operated by the means member for controlling the circuit activity.

17. An instrumentality as in claim 2 characterized in that the member is normally maintained in its charge receiving position by a spring, means being provided for moving the member to its charge segregating position in opposition to the spring.

18. In the art of vaporizing fuel for internal combustion engines, a fuel vaporizing instrumentality adapted to be positioned relative to the flow line leading to the intake manifold of the engine, said instrumentality including a casing having a vaporizing retort positioned above and permanently open to such flow line, a vaporizing unit within the retort adapted to be rendered active at will, a fuel reservoir in superposed relation to the retort and spaced therefrom, means interposed between the reservoir and retort for transferring in bulk a charge of fuel of predetermined and definite amount from the reservoir to the retort at will, the point at which the bulk charge is received by the retort corresponding to the point of vaporizing activity upon the charge, and control means common to said vaporizing unit and said transfer means for producing charge delivery in substantial concurrence with the beginning of unit activity.

19. An instrumentality as in claim 18 characterized in that the instrumentality elements are operatively related to cause the charge to be segregated from the content in the reservoir in approximate concurrence

with the beginning of the vaporizing period.

20. In the art of vaporizing fuel for internal combustion engines, a fuel vaporizing instrumentality adapted to be positioned relative to the flow line leading to the intake manifold of the engine, said instrumentality including a casing having a retort positioned above and permanently open to the flow line, a fuel reservoir in superposed relation thereto and spaced therefrom, said retort having a heating unit adapted to receive and vaporize a charge of fuel delivered to it in bulk, means interposed between the reservoir and retort for transferring in bulk a charge of fuel of predetermined and definite amount from the reservoir to the heating unit at will, the point at which the bulk charge is received by the retort corresponding to the point of vaporizing activity upon the charge, and control means common to the heating unit and said transferring means for producing charge delivery in substantial concurrence with the beginning of unit activity.

21. An instrumentality as in claim 20 characterized in that the heating unit is rendered active at will by the control means and that the transfer means activity and inactivity is by movements in a rotative direction, the control means being operative to provide such rotative movements by the operation which renders the heating unit active and inactive.

22. An instrumentality as in claim 20 characterized in that the transfer means is in open communication with the reservoir during periods of means inactivity and is movable rotatively to produce transfer activity and concurrent charge segregation.

23. An instrumentality as in claim 20 characterized in that the heating unit is positioned out of the direct flow-path to the manifold and is of materially less dimensions than the internal dimensions of the retort and is positioned in generally spaced-apart relation to the retort walls.

24. An instrumentality as in claim 20 characterized in that the vaporizing agency of the heating unit is an electric circuit containing a resistance coil, the control means being operative to control the making and breaking of such circuit.

25. An instrumentality as in claim 18 characterized in that the transfer means includes an air vent rendered active during the fuel-transferring period.

26. An instrumentality as in claim 18 characterized in that said transfer means includes an air vent rendered active during fuel-transferring activity and rendered inactive when such means is receiving the succeeding charge.

27. An instrumentality as in claim 18 characterized in that delivery of the charge

from the transfer means is aided by an air vent rendered active by the control means activity in segregating the charge.

28. An instrumentality as in claim 20 characterized in that the vaporizing agency of the heating unit is an electric circuit containing a resistance coil with the circuit including a circuit make and break device, the transfer means being operatively con-

nected to said device through the control means in such manner that the movements of the transfer means between its limits of movement actuates the device to control the making and breaking of such circuit.

In testimony whereof we affix our signatures.

CHARLES F. LARZELERE.

CHARLES H. NEUMEYER.
